UNITED STATES PATENT OFFICE.

ALBERT W. PEARSALL, OF LOWELL, MASSACHUSETTS, ASSIGNOR TO LAMSON CONSOLIDATED STORE SERVICE COMPANY, OF NEWARK, NEW JERSEY, A CORPORATION OF NEW JERSEY.

PNEUMATIC-DESPATCH-TUBE APPARATUS.

No. 926,823.

Specification of Letters Patent.

Patented July 6, 1909.

Application filed May 11, 1906. Serial No. 316,289.

To all whom it may concern:

Be it known that I, ALBERT W. PEARSALL, of Lowell, in the county of Middlesex and State of Massachusetts, have invented certain new and useful Improvements in Pneumatic-Despatch-Tube Apparatus, of which the following is a specification.

My invention relates to improvements in pneumatic despatch tube apparatus and particularly to that type of apparatus in which the propelling fluid is of greater than the atmospheric pressure, the carrier being transmitted in either direction through a single tube, and the propelling fluid being supplied through supply pipes connecting each end of the transmission tube with the source of air supply.

The objects of this invention are to provide a reliable and easily operable means for introducing the operating fluid to propel the carrier and to maintain the flow of the propelling fluid and quickly and positively cut off the supply of air upon the delivery of the carrier.

The device shown and described in this application is an improvement on that covered by U. S. Letters Patent #640,020 dated Dec. 26, 1899.

In this device means are provided for preventing the air from directly acting upon the diaphragm when the pressure is first admitted to the system. There is further provided a type of valve which offers but slight resistance to the operating force and at the same time performs the function of admitting pressure, cutting off the flow of pressure from the source of supply and automatically relieving the pressure in the transmission tube after the delivery of the carrier thereby rendering noiseless the exhaust of air pressure remaining in the transmission tube. An introduction valve is also provided which is seated by the action of the air in the transmission tube thereby doing away with the noise imparted by the use of an ordinary flap valve.

In the accompanying drawings which illustrate a construction embodying my invention, Figure 1 is a sectional elevation of the terminal in its normal position. Fig. 2 is a sectional elevation of the terminal showing the position of parts in operating for transmission. Fig. 3 is an enlarged sectional elevation of a portion of Fig. 2.

Like letters of reference refer to like parts throughout the several views.

The transmission tube A is connected with the source of pressure E through the medium of the valve casing B, port A' and the hollow column C containing the introduction valve C', the valve casing B being mounted on cabinet D and cabinet plate D'. The valve C' is normally open and operates on the rollers C² which travel on the inclined track C³ which track at the valve seat C⁴ is depressed sufficiently to allow the proper seating of the valve C' and the retaining of said valve while the air pressure is acting in tube A. This valve is actuated by means of the link lever C⁵ which is fixed to the shaft C⁶ projecting through the column C, the outer end of said shaft carrying the fixed lever C⁷ pivoted to the connecting rod C⁸ which is pivoted to the lever F at F'. A helical spring surrounds shaft C⁶ on the outside of the column C and is adapted to return valve C' to open position when the pressure in the tube A is relieved. This spring also restores the trip F⁶ to normal position through the link 8 and lever F.

The lever F is movably mounted on the shaft F² to which the operating handle F³ and lever F⁴ are fixed, the whole being supported by the ears F⁵ projecting from the side of the valve casing B. Fixed to the lever F is the trip F⁶ and the lock lever F⁷, a helical spring F⁸ being interposed between the fixed lever F⁴ and the lever F. The roll F⁹ carried on the end of lever F⁴ is adapted to make rolling contact with the valve stem B⁹ when the handle F³ is moved to the position marked X. The valve shaft B³ is fixed to the valve B' by the pin B¹⁴. The valve B' is slidably mounted upon the shaft B³ within the casing B and carries the pivoted catch B⁴ which operates through the slot B⁷ and is adapted to engage with a recess B⁵ in said shaft B³. The flange B⁸ on the valve B' is held against the head of the valve casing B by the spring B⁶ mounted on the shaft B³ and between the head B⁹ and the valve B'. The valve B' is held against the valve B² by the spring B¹⁰ interposed between said valve and the inner head of the casing B. The circumferential recess B¹¹ in the valve B' registers with the port B¹² normally closing the air admission to the transit tube. The annular chamber G formed between the

valves B' and B² is normally in communication with the pipe G' which connects with the diaphragm cylinder G² in which the sliding piston G³ is mounted. The lower part 5 of the diaphragm cylinder G² connects with the diaphragm chamber G⁴ by the port G⁵ and the upper part of said cylinder is separated from the diaphragm chamber G⁴ by the plug G⁶. The upper part of the cylinder G² 10 is connected with the atmosphere by the port G⁷ graduated and controlled by the screw G⁸. Attached to the diaphragm G⁹ which is clamped to the upper part of the diaphragm chamber G⁴ by the diaphragm cap G¹⁰ is the 15 stem G¹¹; surrounding said stem is a helical spring G¹² interposed between the diaphragm G⁹ and the adjustment cap G¹³. To the upper end of the stem G¹¹ is pivoted the slotted lever H which is centrally pivoted to the extension H' of the diaphragm casing. The 20 opposite end of said lever is adapted to engage and lock the valve B² which valve B² normally closes the port H² to the atmosphere. The carriers are adapted to discharge 25 through the chute J into the receptacle J'.

The operation is as follows: The carrier is introduced through the opening in the valve seat C⁴ into the transit tube A and held therein while the handle F³ is moved to the position shown in full lines (Fig. 2) which closes the valve C' through the medium of the lever F, rod C⁸ and levers C⁷ and C⁵; a continued movement of said handle to the position shown at X, forces the valve B' against the 30 spring B¹⁰ to the position shown in Fig. 2 thereby uncovering the port B¹² allowing the pressure to flow through the valve casing B and port A' and column C to the transmission tube A, thereby impelling the carrier to 35 the opposite end of the line and firmly seating the valve C'. The movement of the handle to the position shown in dotted lines X compresses the spring F⁸ without further movement being imparted to the lever F but 40 imparting movement to the valve B' through the shaft B³ which causes the latch B⁴ to engage with the groove B⁵ in said shaft locking the two valves together and balancing the 45 valves against the air pressure. The valve B² is locked by the lever H and held locked by tension of the diaphragm spring G¹². The carrier having discharged from the opposite 50 end of the transit tube A through a terminal similar to that shown in Fig. 1, strikes the trip F⁶ which is fixed to the lever F and imparts a partial movement to the valve C' when the pressure in the system impinges upon the upper surface of said valve casing causing the same to travel down the inclined 55 rails to a firm seating on the valve seat C⁴ and preventing the escape of air in the transit tube and causing the pressure thereon to increase thereby acting on the opposite or despatching terminal through the pipe G 60 slowly forcing the piston G³ to the upper part 65

of the diaphragm cylinder G² against the graduated escape of the air confined in the upper part of said cylinder, the escape of the air through the port G⁷ being regulated by the screw G⁸. When said piston reaches its 70 limit of travel the port G⁵ is uncovered admitting sufficient pressure to actuate the lever H⁸ through the medium of the diaphragm G⁹ releasing the valve B² which is locked to the valve B' when the spring B¹⁰ forces both 75 forward,—the valve B' to normal position and the valve B² sufficiently to cause the catch B⁴ to engage the upper part of the slot B⁷ releasing said catch, when the port H² will have been opened, allowing the escape 80 of the pressure remaining in the system, whereupon the spring B⁶ will force the valve B² back with its collar B⁸ against the head of the valve casing and said valve will assume its normal position and close the port H². 85 The lock lever F⁷ having been released, the lever F and valve C' are moved to normal position by spring F⁸.

Having thus described the nature of my invention and set forth a construction embodying the same, what I claim as new and desire to secure by Letters Patent of the 90 United States is:

1. In a pneumatic despatch tube apparatus, a carrier transmission tube arranged 95 to receive and discharge carriers at either terminal, a valve arranged at each terminal of the tube to control the entrance thereto, a connection provided adjacent each terminal to supply air under pressure, an air valve in 100 said connection controlling the passage of air therethrough, means for operating the terminal valve to close the same, mechanism actuated by said means and operating to open said air valve in the connection, a locking device coöperating with said mechanism to hold the air valve in open position, a member arranged to be actuated by the impact of the carrier after its discharge from the tube and coöperating with the terminal valve- 110 operating means to impel said valve to close, and means operated by the excess air pressure in the tube caused by the closing of the terminal valve after the discharge of the carrier for releasing said locking device and 115 thereby permit the closing of the air valve in the connection supplying air to the transmission tube.

2. In a pneumatic despatch tube apparatus, a carrier transmission tube arranged 120 to receive and discharge carriers at either terminal of the tube to control the entrance thereto, a connection provided adjacent each terminal to supply air under pressure, an air valve in said connection controlling the passage of air therethrough, means for operating the terminal valve to close the same, mechanism actuated by said means and operating to open said air valve in the connection, a locking device coöperating with said mechanism 125

- to hold the air valve in open position, a member arranged to be actuated by the impact of the carrier after its discharge from the tube and coöperating with the terminal valve- 5 operating means to impel said valve to close, means operated by the excess air pressure in the tube caused by the closing of the terminal valve after the discharge of the carrier for releasing said locking device and thereby 10 permit the closing of the air valve in the connection supplying air to the transmission tube.
- 15 3. In a pneumatic despatch tube apparatus, a carrier transmission tube arranged to receive and discharge carriers at either terminal, a valve arranged at each terminal of the tube to control the entrance thereto, 20 connection provided adjacent each terminal to supply air under pressure, an air valve in said connection controlling the passage of air therethrough, means for operating the terminal valve to close the same, mechanism 25 actuated by said means and operating to open said air valve in the connection, a locking device coöperating with said mechanism to hold the air valve in open position, a member arranged to be actuated by the impact of 30 the carrier after its discharge from the tube and coöperating with the terminal valve- operating means to impel said valve to close, means operated by the excess air pressure in the tube caused by the closing of the terminal 35 valve after the discharge of the carrier for releasing said locking device and thereby permit the closing of the air valve in the connection supplying air to the transmission tube, and means for timing the release of said 40 locking device.
4. In a pneumatic despatch tube apparatus, a carrier transmission tube arranged to receive and discharge carriers at either terminal, a valve arranged at each terminal of the tube to control the entrance thereto, a connection provided adjacent each terminal to supply air under pressure, an air valve in said connection controlling the passage of air therethrough, means for operating the terminal valve to close the same, mechanism 45 actuated by said means and operating to open said air valve in the connection, a locking device coöperating with said mechanism to hold the air valve in open position, a member arranged to be actuated by the impact of the carrier after its discharge from the tube and coöperating with the terminal valve operating means to impel said air valve to close, means operated by the excess air pressure in the tube caused by the closing of the terminal 50 valve after the discharge of the carrier for releasing said locking device and thereby permit the closing of the air valve in the connection supplying air to the transmission tube, and means for graduating the action of said 55 excess air pressure upon said locking device.
5. In a pneumatic despatch tube apparatus, a carrier transmission tube arranged to receive and discharge carriers at either terminal, a valve arranged at each terminal of the tube to control the entrance thereto, a connection provided adjacent each terminal to supply air under pressure, an air valve in said connection controlling the passage of air therethrough, means for operating the terminal valve to close the same, mechanism 60 actuated by said means and operating to open said air valve in the connection, a lever for holding said air valve open, a diaphragm to which said lever is connected on one side and adapted to be actuated on the opposite side by the excess of air pressure within said transmission tube to operate said lever and thereby 65 release and permit the closure of said air valve, and mechanism arranged to prevent the direct action of the air pressure on said diaphragm when first admitted to said transmission tube.
6. In a pneumatic despatch tube apparatus, a carrier transmission tube arranged to receive and discharge carriers at either terminal, a valve arranged at each terminal of the tube to control the entrance thereto, a connection provided adjacent each terminal to supply air under pressure, an air valve in said connection controlling the passage of air therethrough, means for operating the terminal valve to close the same, mechanism 70 actuated by said means and operating to open said air valve in the connection, a lever for holding said air valve open, a diaphragm to which said lever is connected on one side and adapted to be actuated on the opposite side by the excess of air pressure within said transmission tube to operate said lever and thereby 75 release and permit the closure of said air valve, and mechanism arranged to prevent the direct action of the air pressure on said diaphragm when first admitted to said transmission tube.
7. In a pneumatic despatch tube apparatus, a carrier transmission tube arranged to receive and discharge carriers at either terminal, a valve arranged at each terminal of the tube to control the entrance thereto, a connection provided adjacent each terminal to supply air under pressure, an air valve in said connection controlling the passage of air therethrough, means for operating the terminal valve to close the same, mechanism 80 actuated by said means and operating to open said air valve in the connection, a lever for holding said air valve open, a diaphragm to which said lever is connected on one side and adapted to be actuated on the opposite side by the excess of air pressure within said transmission tube to operate said lever and thereby 85 release and permit the closure of said air valve, and mechanism arranged to prevent the direct action of the air pressure on said diaphragm when first admitted to said transmission tube.
8. In a pneumatic despatch tube apparatus, a carrier transmission tube arranged to receive and discharge carriers at either terminal, a valve arranged at each terminal of the tube to control the entrance thereto, a connection provided adjacent each terminal to supply air under pressure, an air valve in said connection controlling the passage of air therethrough, means for operating the terminal valve to close the same, mechanism 90 actuated by said means and operating to open said air valve in the connection, a lever for holding said air valve open, a diaphragm to which said lever is connected on one side and adapted to be actuated on the opposite side by the excess of air pressure within said transmission tube to operate said lever and thereby 95 release and permit the closure of said air valve, and mechanism arranged to prevent the direct action of the air pressure on said diaphragm when first admitted to said transmission tube.
9. In a pneumatic despatch tube apparatus, a carrier transmission tube arranged to receive and discharge carriers at either terminal, a valve arranged at each terminal of the tube to control the entrance thereto, a connection provided adjacent each terminal to supply air under pressure, an air valve in said connection controlling the passage of air therethrough, means for operating the terminal valve to close the same, mechanism 100 actuated by said means and operating to open said air valve in the connection, a lever for holding said air valve open, a diaphragm to which said lever is connected on one side and adapted to be actuated on the opposite side by the excess of air pressure within said transmission tube to operate said lever and thereby 105 release and permit the closure of said air valve, and mechanism arranged to prevent the direct action of the air pressure on said diaphragm when first admitted to said transmission tube.
10. In a pneumatic despatch tube apparatus, a carrier transmission tube arranged to receive and discharge carriers at either terminal, a valve arranged at each terminal of the tube to control the entrance thereto, a connection provided adjacent each terminal to supply air under pressure, an air valve in said connection controlling the passage of air therethrough, means for operating the terminal valve to close the same, mechanism 110 actuated by said means and operating to open said air valve in the connection, a lever for holding said air valve open, a diaphragm to which said lever is connected on one side and adapted to be actuated on the opposite side by the excess of air pressure within said transmission tube to operate said lever and thereby 115 release and permit the closure of said air valve, and mechanism arranged to prevent the direct action of the air pressure on said diaphragm when first admitted to said transmission tube.

In testimony whereof, I have signed my name to this specification in the presence of two subscribing witnesses, this eighth day of May A. D. 1906.

ALBERT W. PEARSALL.
